UNITED STATES PATENT OFFICE.

EDWARD H. WELLS, OF MONTCLAIR, NEW JERSEY, ASSIGNOR TO THE BABCOCK & WILCOX COMPANY, OF RAYONNE, NEW JERSEY, A CORPORATION OF NEW JERSEY.

BOILER FURNACE.

Application filed August 9, 1921. Serial No. 490,855.

My present invention relates to an arrangement by which the tubes of water tube boilers may be readily cleaned.

In the operation of steam boilers the lower water tubes will sometimes have formed thereon in the operation of the boiler a coating of slag, the removal of which is difficult.

One of the objects of my invention is to provide a furnace arranged so that tools may be readily inserted from the exterior of the furnace to scrape or cut off such accumulated slag.

As an illustrative form of my invention I have shown it applied to a boiler of the horizontally inclined water tube type, Fig. 1 being an interior view of a portion of such a boiler and its furnace with one form of my invention applied thereto, some of the parts being in section and others broken away; Fig. 2 is a sectional elevation of the arrangement shown in Fig. 1, the section being taken through the center line of any one of the openings; Fig. 3 is a plan view partly in section taken on the line 3—3 of Fig. 2; Fig. 4 is a perspective view of one of the tiles used in my illustrative form; Fig. 5 is a side view of Fig. 4; Fig. 6 is a front view of the tile illustrated in Figs. 4 and 5; Figs. 7 and 8 are front views of two complementary tiles, the tile shown in Fig. 8 being the same as that shown in Fig. 6; Fig. 9 is a side view of Fig. 8; Fig. 10 is a plan view of Fig. 8, and Fig. 11 is a horizontal section of Fig. 7.

Similar reference characters indicate similar parts in the several views.

In the drawings, 10, 10 represent water tubes connected to headers 11, 11 in the well-known manner. A wall of the furnace for the boiler is shown at 12 and is positioned beneath the headers 11. The usual boiler casting 13 is provided to cover the boiler parts and may also cover the wall 12, a heat insulating material 14 being shown between the casting 13 and the wall 12.

At the top of the wall 12 is a course of special tile made up, in the form illustrated, of right and left-hand blocks 15, 16 provided with alternate projections 17 and recesses 18 by which the tiles are interlocked with each other to prevent displacement. This course of tile may be directly at the top of the wall 12 or at some distance below the top.

The tiles 15, 16 are formed so that when

in position, an opening 19 will extend 55 through each pair of tiles, this opening being preferably in the form shown, with a generally conical shape with the axis of the cone at an angle to the horizontal and with the outer end of the opening much smaller 60 than the inner end thereof. Preferably, the lower edge of the opening 19 will be horizontal, as shown in Fig. 2, and the upper edge will be at an angle to the horizontal.

The size and shape of the opening and its 65 location in relation to the headers 11 and the top of wall 12 is such that a straight tool, such as T, may be inserted at an angle of about 30 degrees to the horizontal through the opening 19, and the end of the 70 tool made to contact with the tube 10 to within a short distance of its high end inside the furnace wall. The tool may also be made to contact with that part of the tube remote from the wall 12, over which 75 the gases flow on leaving the furnace, as will be apparent from Figure 2. By employing a tool with a curved end, it may be made to contact with the tube 10 up to the high end directly inside of the furnace 80 wall. To effect this, in addition to properly shaping the openings in the tiles, the faces of the openings are set inside of the outer face of the wall and a space for access to the 85 openings is thereby provided above the top of the wall, said space being sealed so as to prevent leakage of air into the setting. The preferable form of tool is an air lance, that is, a tool made of a tube or pipe, through 90 which compressed air is circulated; the circulation of the compressed air through the tube or pipe prevents the pipe from overheating when the slag is removed with the boiler and furnace in operation. Again, the action of the air impinging on the slag in 95 itself assists in removing the slag.

By having the opening 19 flared in the horizontal direction also, as shown in Fig. 3, the tool may be worked from side to side to cover more than one tube 10 in a horizontal 100 row of such tubes.

Preferably, the tiles 15, 16 are much thinner than the wall 12 so that a large angular motion may be given to the tool T through a 105 relatively small opening and consequently a relatively small tile. Closures for the outer ends of the openings 19 are also provided, the form illustrated comprising doors 20

slidely mounted on metal frames 21 attached to the casing 13 which is carried inward, as shown in Fig. 2, to a point adjacent the outer face of the tiles 15, 16.

5 In the illustrative form of the invention, when it is desired to clean the lower tubes 10, a closure 20 is moved to open position, as shown at the left of Fig. 3, and the tool T inserted through the opening 19 to cut and 10 remove the accumulated slag from all parts of the tubes 10 accessible through the opening 19. The tool T is successively inserted through the several openings 19 by which all of the tubes 10 will be ultimately reached 15 and cleaned.

It will be understood that the arrangement shown in the drawings is merely illustrative and that it may be varied within wide limits. For instance, if desired, instead 20 of making up the tiles in two parts for each opening, there may be a single tile for each opening, with the opening formed in the middle of the tile. It will also be understood that various forms of openable closures for the openings 19 may be used. 25

I claim:—

1. In a furnace for a boiler having horizontally extending water tubes connecting water compartments at their ends, a refractory wall beneath and adjacent to the ends of 30 the tubes, refractory tiles at the upper part of the wall and having a horizontally extending series of openings formed therein which are enlarged inwardly to permit entry 35 of a tool selectively therethrough and access to the lower water tubes, metal framing out-

side the row of tiles and having access openings registering with the openings in the tiles, and movable closures for the framing openings.

40

2. In a furnace for a boiler having horizontally extending water tubes connecting water compartments at their ends, a refractory wall beneath and adjacent to the ends of the tubes, refractory tiles at the upper part 45 of the wall, said tiles having interlocking projections and recesses and having a horizontally extending series of openings formed therein which are enlarged inwardly to permit entry of a tool selectively therethrough 50 and access to the lower water tubes, metal framing outside the row of tiles and having access openings registering with the openings in the tiles, and movable closures for the framing openings.

55

3. In a furnace for a boiler having horizontally extending water tubes connecting water compartments at their ends, a refractory wall beneath and adjacent to the ends of the tubes, refractory tiles at the upper 60 part of the wall and having a horizontally extending series of openings formed therein which are enlarged inwardly to permit entry of a tool selectively therethrough and access to the lower water tubes, metal framing outside the row of tiles and having access openings registering with the openings in the tiles, movable closures for the framing openings, and an outer metal casing to which the metal framing is connected.

EDWARD H. WELLS.
